US0D1087718S

(12) **United States Design Patent** (10) **Patent No.:** **US D1,087,718 S**
(45) **Date of Patent:** **** Aug. 12, 2025**

(54) **IMPACT TOOL**

(71) Applicant: **Ingersoll-Rand Industrial U.S., Inc.**,
Davidson, NC (US)

(72) Inventors: **Roger B. Davis**, Clinton, NJ (US);
Edward Charles Eardley, Easton, PA (US); **Ryan S. Amend**, Bethlehem, PA (US)

(73) Assignee: **Ingersoll-Rand Industrial U.S., Inc.**,
Davidson, NC (US)

(**) Term: **15 Years**

(21) Appl. No.: **29/964,651**

(22) Filed: **Sep. 24, 2024**

Related U.S. Application Data

(63) Continuation of application No. 29/888,751, filed on Apr. 4, 2023, now Pat. No. Des. 1,050,841.

(57) **CLAIM**

The ornamental design for an impact tool as shown and described.

DESCRIPTION

FIG. 1 is an isometric view of an impact tool.

FIG. 2 is another isometric view of the impact tool of FIG. 1.

FIG. 3 is a top plan view of the impact tool of FIG. 1.

FIG. 4 is a bottom plan view of the impact tool of FIG. 1.

FIG. 5 is a front elevation view of the impact tool of FIG. 1.

FIG. 6 is a rear elevation view of the impact tool of FIG. 1.

FIG. 7 is a right side elevation view of the impact tool of FIG. 1; and,

FIG. 8 is a left side elevation view of the impact tool of FIG. 1.

Portions of FIGS. 1 through 8 are shown in evenly spaced broken lines illustrating portions of the article that form no part of the claimed design. The dash-dot-dash broken lines in the drawings illustrate the boundary of the claimed design, which forms no part thereof.

1 Claim, 8 Drawing Sheets
